(57) **CLAIM**

The ornamental design for a pick-up cartridge as shown and described.

DESCRIPTION

FIG. 1 is a front, top, left side perspective view of a pick-up cartridge;

FIG. 2 is a rear, bottom, right side perspective view of the pick-up cartridge;

FIG. 3 is a front elevational view of the pick-up cartridge;

FIG. 4 is a rear elevational view of the pick-up cartridge;

FIG. 5 is a top plan view of the pick-up cartridge;

FIG. 6 is a bottom plan view of the pick-up cartridge;

FIG. 7 is a right-side elevational view of the pick-up cartridge;

FIG. 8 is a left-side elevational view of the pick-up cartridge; and,

FIG. 9 is a sectional view of the pick-up cartridge taken along line 9-9 of FIG. 7 with the internal system partially omitted.

Portions of the drawings shown in broken lines form no part of the claimed design.

1 Claim, 9 Drawing Sheets
